Machine for Rolling Axles.

No. 241,106.

Patented May 3, 1881.

UNITED STATES PATENT OFFICE.

JOHN H. WHITNEY, OF NEW YORK, N. Y.

MACHINE FOR ROLLING AXLES.

SPECIFICATION forming part of Letters Patent No. 241,106, dated May 3, 1881.

Application filed April 22, 1880. (No model.)

To all whom it may concern:

Be it known that I, JOHN HENRY WHITNEY, of the city, county, and State of New York, have invented an Improved Machine for Rolling Axles, of which the following is a specification.

The object of my invention is to provide a new and improved machine for rolling axles, rivets, bolts, and other articles in a simple and effective manner.

The metal is fed into the machine through a suitable guide consisting of a loose flanged short tube held between two or more rollers or adjustable slides, the metal being held between the rollers by a pair of automatic tongs, which close as the work progresses.

In the accompanying drawings, Figure 1 is a front elevation of my improved rolling-machine, showing the same arranged for rolling axles. Fig. 2 is a front elevation of the same, showing it modified and arranged for rolling button-head rivets. Fig. 3 is an end elevation of the same. Fig. 4 is a cross-sectional elevation on the line *x x*, Fig. 2, showing the arrangement of the cam-wheel. Fig. 5 is a side elevation of the apparatus for guiding the metal into the machine. Fig. 6 is a plan view and end elevation of the same. Fig. 7 is a cross-sectional elevation of a modification of the apparatus for guiding the metal into the machine. Fig. 8 is a front elevation of the same. Fig. 9 is an end and side elevation of the tongs for holding the work between the rollers. Fig. 10 shows the rollers as modified for rolling rivets with truncated cone-heads.

Similar letters of reference indicate corresponding parts.

The shafts A and B are journaled in the frame C, and have spur-wheels D D mounted on one end, and rollers E E of some suitable shape mounted on the other end. The spur-wheels D D engage with a pinion, F, mounted on a shaft, G, provided with a fly-wheel, H, a fixed pulley, I, and a loose pulley, I'. The journal J of the outer end of the upper shaft is pivoted, as shown in dotted lines, so as to permit the roller end of the said shaft to be slightly raised for a purpose that will be set forth hereinafter. The upper shaft, A, is surrounded by a sleeve, K, upon the outer end of which a geared wheel, L, (engaging with a

pinion, M, on the shaft B,) is mounted, and a cam-wheel, N, resting upon a smooth wheel, O, on the shaft B, is mounted on the said sleeve K. The wheel L and pinion M may be replaced by 55 a worm-wheel, L', and a worm, M', especially when a very slow movement, which is independent of the movement of the shafts A and B, is desired.

The rollers E E, which are used to roll axles, 60 are beveled according to the bevel that the spindle of the axle is to have, and are provided with grooves *a a* near the outer ends, which grooves form the collar between the axle and the spindle.

If rivets are to be rolled, the rollers E' E' will be composed of a series of disks, *b b*, which are mounted on the shafts, and are held by an end plate, *c*, which has the shape of the head of the rivet. If rivets with truncated cone 70 heads are desired, knives P P' must be attached to both ends of one or both rollers E' E', for the purpose of cutting off the metal. The rollers are pressed against each other by a strong spiral or other spring, Q, the tension 75 of which can be regulated by means of a screw operated by a hand-wheel, R. The metal is fed into the machine through a guide placed in front of the ends of the rollers, and consisting of a flanged tube, S, mounted between three or 80 four rollers, T T, on a suitable frame, *d*; or the tube S can be loosely held by two or more L-shaped slides, U, which can be adjusted according to the diameter of the tube S, and are held, when adjusted, by means of screws *e e* 85 passing through the slots *f f* in the slides U, and entering the frame or standard *g*. The tube is mounted between the rollers so as to permit it to be rotated freely with the bar passing through it. The sliding plates are adjustable to suit the diameter of the tube, which must have a perforation corresponding to the diameter of the rod that is to be introduced between the rollers. The work is held between the rollers E by a pair of tongs formed of two 90 L-shaped levers, V, pivoted below the shaft A in such a manner that the shanks *h* of the said levers embrace the said shaft A. The inner sides of the shanks *h* are rounded and then beveled, so that they are square when the shaft A 95 descends. The lower ends of the levers V are drawn apart by spiral or other suitable springs, 100

W W. The tubes S are varied in size, according to the size of the work.

The operation is as follows: As the pinion F is between the two wheels D D, it is evident 5 that they will both rotate in the same direction, and as the pinion M is much smaller than the spur-wheel L it is evident that the sleeve K will not rotate as rapidly as the shaft A. If the shaft G is rotated from left to right, the 10 shafts A and B and the rollers E E will both be rotated from right to left, and the cam-wheel N will be rotated from left to right. If the cam proper, m, only of the cam-wheel N rests on the smooth wheel O, the rollers E E will be 15 at the maximum of separation, and the hot iron is now passed through the guide-tube S into the space between the rollers. As the cam-wheel N continues to rotate, the rollers come nearer to each other, and the pressure of the 20 spring Q upon the rollers causes a spreading of the iron; but as the rollers rotate much more rapidly than the cam-wheel N, the result is that the rivet or axle is being formed as rapidly as the iron spreads. If the cam-wheel 25 N is in the position shown in Fig. 4, the rollers are as close to each other as they possibly can be, and the next moment they will begin to separate very rapidly, permitting the end of the iron rod X to be pushed in between them 30 again. If the object can only be formed with great difficulty, the worm M' and the worm-wheel L' should preferably be used, as with them the speed of the sleeve K can be reduced as much as may be desired or necessary. As 35 the cam-wheel N raises the roller E of the shaft A at every revolution, it is necessary that the journal J be pivoted. If the shaft A is raised the lower ends of the levers V are drawn apart by the springs W W, causing the upper shanks,

h h, to lie up closely against the shaft A; but as the shaft A gradually descends it spreads the shanks h, and the lower ends of the levers V are brought together, holding the work between them. The work gets thinner as the shaft A descends, and at the same time the 45 lower ends of the levers V are pressed closer together. As soon as the shaft A rises the lower ends of the levers V are drawn apart again by the springs W W.

In the above-described manner axles, rivets, 50 bolts, or any other similar articles can be rolled rapidly and in first-class quality. For making axles two machines may be preferably used at the same time, each rolling one end of the axle.

Having thus fully described my invention, I 55 claim as new and desire to secure by Letters Patent—

1. The combination, with the shafts A and B, of the sleeve K, the cog-wheel L, pinion M, cam-wheel N, and smooth wheel O, substantially as herein shown and described, and for the purpose set forth.

2. The roller-shaft B, pinion M, and smooth wheel O, in combination with the pivoted bearing J, sleeve K, wheel L, cam N, roller-shaft 65 A, screw and hand wheel R, and spring Q, as and for the purpose specified.

3. The combination, with the shaft A, provided with a pivoted journal, J, of the L-shaped levers V, pivoted to the frame at the 70 sides of the shaft A, substantially as herein shown and described, and for the purposes set forth.

JOHN H. WHITNEY.
